UNITED STATES PATENT OFFICE.

JOHN HENSON KESSLER, OF VINELAND, NEW JERSEY.

SPECIFIC-GRAVITY TESTER.

1,360,537.

Specification of Letters Patent. Patented Nov. 30, 1920.

Application filed September 23, 1919. Serial No. 325,814.

To all whom it may concern:

Be it known that I, JOHN H. KESSLER, a citizen of the United States, residing at Vineland, in the county of Cumberland and State 5 of New Jersey, have invented a new and useful Improvement in Specific-Gravity Testers, of which the following is a specification.

This invention relates to apparatus for testing specific gravity, and particularly to 10 apparatus designed for use with cooked food products to determine accurately their condition and quality.

The special object of the tester is to provide a means to be used when cooking down 15 fruit and vegetable pulp or juices so that a uniform density will obtain with every batch turned out, thereby making it easy for the manufacturer to deliver a standard product to the trade.

20 For a complete understanding of the invention, the drawing which accompanies and forms a part of this specification should be referred to.

In the drawing:—

25 Figure 1 is an elevation of the tester ready to take up a sample, and

Fig. 2 is an elevation partly in section of the same with a charge of material to be tested.

30 Speaking generally the tester in its preferred form embodies a glass vessel having a tube or stem 5, a buoyancy bulb 6, a sample bulb or chamber 7, a neck 8 connecting the two bulbs, a valve chamber 9 and a tube 10, 35 all of which are integral with each other and connect to form a continuous passageway.

The stem 5 is hollow and has graduations 11 etched or otherwise formed on its inner or outer surface. At its lower end the stem 40 connects with the buoyancy bulb 6 which may be of any desired size and shape. A short hollow neck 8 connects the lower end of the buoyancy bulb with the upper end of the sample chamber 7. Midway between the 45 two bulbs on the neck, a mark 12 is provided for a purpose to be described.

The lower or sample holding bulb 7 is preferably of the same size and shape as the buoyancy bulb, but may be of any other form 50 and size. At the lower end of the sample chamber is connected the valve chamber 9. In the valve chamber is placed a valve stem 13 preferably of glass, with a handle 14 and a port 15. The latter runs diagonally through the stem as shown. The tube 10 is connected to the valve chamber on the lower side but

is offset with respect to the remainder of the vessel, so that only when the valve stem is rotated to place the ends of the port 15 in communication with the sample chamber and 60 the tube, is there a possibility of material passing into the chamber from the tube.

The device is used as follows: With the valve in the position shown in Fig. 1 the offset tube is inserted in the substance to be 65 tested, and the operator puts the upper or stem end of the instrument in his mouth and sucks. The substance will rise to the desired height, approximately to the mark 12, when the operator closes the valve and thus 70 entraps the desired sample in the tester. If there is more in the tester than is needed it is easy to let a little escape by opening the valve and shutting the same the moment the level of the sample alines with the mark 12. 75 The tester with its sample is now put in a vessel of water, whereupon it will float upright, due to the empty buoyancy chamber and the filled sample holding bulb below. The heavier the sample is, the lower the instrument will float. In any case the level 80 of the instrument is read by looking along the surface of the water and reading the graduation on the stem where the stem enters the water. After the reading the sample 85 can be returned to the batch from which it was taken, since the water cannot reach it.

This invention is specially designed for use in testing food products during cooking, such as catchup, maple syrup, jelly, and 90 others too numerous to mention. It can, however, be used in the determination of the specific gravity of any liquid or fluent material, whether or not fit for food.

One advantage of the offset tube 10 is 95 that it enables the operator to place the end of the tester in a vessel containing cooking foodstuffs and draw up a sample into the tester by applying his lips at the upper end without being subjected to the steam arising 100 from the cooking. A further advantage is that the device always floats in an upright position, because the valve stem is counterbalanced. Were this tube not offset, the valve stem would make the tester float in 105 an inclined position, in which it would be difficult if not impossible to get a correct reading of the specific gravity.

While the invention has been described with considerable detail, it is clear that the 110 description may be departed from in many particulars without departing from the

scope of the invention as defined in the appended claims. For example, the mark 12 may be placed elsewhere on the tester than in the particular location specified. The 5 valve may be of a different type from that shown. More than two bulbs may be used for holding the sample and for supplying the necessary buoyancy, and they may be made of different shapes. Other departures from the specific combination may be 10 made.

The tester besides the advantages already mentioned is easily cleaned, and is easily and cheaply manufactured, being made of 15 but two pieces.

What is claimed is:—

1. In a specific gravity tester, a pair of similar bulbs, a neck connecting the two bulbs, a hollow stem communicating with 20 one bulb, a valve in communication with the

other bulb, and a tube depending from and open to the valve and offset with respect to the rest of the device.

2. In a specific gravity tester, a plurality of hollow bulbs, a hollow neck communicating with said bulbs and having a mark thereon, a hollow stem communicating with the uppermost of the bulbs and provided with graduations and open at the top, a valve communicating with the lowermost of the bulbs, and an offset tube opening into and depending from the valve. 25 30

In testimony that I claim the foregoing as my own, I have hereto affixed my signature in the presence of two witnesses.

JOHN HENSON KESSLER, PHG.
